UNITED STATES PATENT OFFICE.

CHARLES FRANZ, JR., OF MILWAUKEE, WISCONSIN.

BINDER POST FOR LOOSE-LEAF BINDERS.

Application filed February 1, 1924. Serial No. 689,923.

To all whom it may concern:

Be it known that I, CHARLES FRANZ, Jr., a citizen of the United States, and resident of Milwaukee, in the county of Milwaukee, 5 and State of Wisconsin, have invented certain new and useful Improvements in Binder Posts for Loose-Leaf Binders; and I do hereby declare that the following is a full, clear, and exact description thereof.

10 This invention relates to loose leaf binders and is particularly directed to a binder post construction.

15 It is well known that binder posts, where they join the binder strips, are subjected to a great deal of lateral stresses which soon weaken and loosen the joint between the post and the binder strip and produce an unsatisfactory condition.

20 Further than this, these binder posts become sufficiently loosened to turn with reference to the binder strip and to cause further trouble.

25 This invention is designed to overcome the above noted defects and objects of such invention are to provide a binder post construction in which the post is securely and rigidly attached to the binder strip, in which provision is made to prevent the turning of the post, and in which a simple and 30 easily produced construction is obtained.

35 An embodiment of the invention is shown in the accompanying drawings, in which:—

Figure 1 is a partial sectional view of a binder strip showing the post in one stage 35 of attachment thereto.

Figure 2 is a partial sectional view showing the post completely attached to the strip.

40 Figure 3 is a plan view of the structure shown in Figure 2.

Figure 4 is a sectional view on the line 4—4 of Figure 3.

Figure 5 is a bottom view of the structure shown in Figure 2.

45 Figure 6 is a fragmentary view of a portion of the binder strip showing the hole which receives the lower end of the post.

The binder comprises a binder strip 1 to which a tubular post 2 is attached. This

50 binder strip may be of any suitable type and may cooperate with a similar strip 3 provided with a downwardly extending post 4 adapted to enter the tubular post 2, as shown in dotted lines in Figures 1 and 2.

55 In forming this binder strip, a circular hole 5 is punched for the reception of the tube 2,

and such hole is provided with one or more notches 6, preferably a pair of diametrically opposed notches being provided as illustrated in Figure 6. The tubular post 2 is formed with an outwardly projecting integral folded flange 7 adjacent one end so as to leave a downwardly projecting lower portion 8. This lower portion 8 is slotted on opposite sides or provided with cut-outs 9 for a purpose hereinafter to appear. After the post is thus formed, the projecting portion 8 is slipped through the aperture 5, as illustrated in Figure 1, and, thereafter, the portion 8 is turned outwardly to form a bottom flange 8', as shown in Figures 2, 4 and 5. The cut out portions 9 permit the flange to flatten without danger of tearing the material and insuring a smooth and even contact between the flange 8' and the bottom of the binder strip 1. Either during this flattening process for the flange 8 or subsequent thereto, the upper flange 7 is pressed downwardly into the notches 6 so that a portion 10 thereof firmly fits and engages the sides of the notches. This is most readily accomplished by providing a tool adapted to surround the tube 2 and provided with projecting portions to form the depressions 11 in the upper side of the flange 7, as shown in Figures 2, 3 and 4.

It is apparent that the portion 10 instead of being formed by projecting the flange 7 into the notches 6 might readily be formed by projecting the flange 8' upwardly into such notches and that one or more notches 6 could be employed.

It will thus be seen that a post construction has been provided for loose leaf binders in which a very secure and firm joint is readily obtained between the tubular post and the binder strip, and in which all danger of rotation of the post or loosening thereof is obviated.

Although one form of the invention has been described in considerable detail, it is to be understood that the invention may be variously embodied and is, therefore, to be limited only as claimed.

I claim:

1. The combination of an apertured binder strip having notches communicating with said aperture, and a tubular post positioned within said aperture and having an integrally formed folded flange intermediate its ends, and in contact with one side of said binder strip and having an outwardly ex-

tending flange positioned upon the opposite side of said binder strip, one of said flanges being pressed axially of said post into said notches.

- 5 2. The combination of a binder strip having an aperture therein provided with notches, a tubular post projecting through said aperture and having a folded outwardly projecting flange in contact with one side
10 of said strip and having an outer flange in

contact with the other side thereof, said outer flange having cut outs therein, and said upper flange having portions pressed downwardly into said notches.

In testimony that I claim the foregoing I 15
have hereunto set my hand at Milwaukee,
in the county of Milwaukee and State of
Wisconsin.

CHARLES FRANZ, JR.
